FREDERICK E. SZEMERE, OF NEW YORK, N. Y.

COMBINATION-GARMENT.

1,192,583.

Specification of Letters Patent.

Patented July 25, 1916.

Application filed August 26, 1915. Serial No. 47,391.

To all whom it may concern:

Be it known that I, FREDERICK E. SZEMERE, a subject of the King of Hungary, and a resident of the city of New York, (borough of the Bronx,) in the county of Bronx and State of New York, have invented a new and Improved Combination-Garment, of which the following is a full, clear, and exact description.

10 The invention relates to garments, such as shown and described in the Letters Patent of the United States, No. 1,152,350, granted to me on August 31, 1915.

15 The object of the present invention is to provide a new and improved combination garment, such as a combination shirt and union suit, rompers, pajamas, chemisettes and bloomers and the like, and arranged to permit the user to readily convert the garment from a loose body garment to one with leg portions and vice versa, and while the garment is in position on the user's body.

20 In order to accomplish the desired result, use is made of a body split in a vertical direction along the median line of the front and the back to form overlying front and back flaps, the flaps being provided with buttonholes and means engaging the buttonholes for fastening the flaps in position to provide leg portions at the lower end of the garment body.

25 A practical embodiment of the invention is represented in the accompanying drawings forming a part of this specification, in which similar characters of reference indicate corresponding parts in all the views.

30 Figure 1 is a front perspective view of the garment as applied to a person; Fig. 2 is a rear perspective view of the same; Fig. 3 is a cross section of the garment with the parts in the position shown in Figs. 1 and 2; Fig. 4 is a front perspective view of the same; Fig. 5 is a front perspective view of the garment as applied to a person and with the 35 parts in a different position from the one shown in Fig. 1; Fig. 6 is a rear perspective view of the same; Fig. 7 is a cross section of the garment with the parts in the position shown in Figs. 5 and 6; and Fig. 8 is a front perspective view of the lower portion 40 of the garment and with the front and back flaps in open position.

45 The body 10 of the garment is split in a vertical direction along the median line of the front to form overlying flaps 11 and 12, of which the flap 11 is provided in its upper

portion with buttons 13 adapted to be engaged by buttonholes 14 formed in the upper portion of the flap 12 to connect the flaps 11 and 12 with each other with a view to close the body of the garment. The lower portions of the flaps 11 and 12 are provided with spaced buttonholes 15 and 16.

50 The lower portion of the back of the body 10 is split in a vertical direction along the median line to form overlying flaps 17, 18 provided in the upper portions with spaced buttonholes 19 and 20 adapted to register with each other and with corresponding buttonholes 15 and 16 on the front flaps 11 and 12. The pairs of registering buttonholes 15, 16 and 19, 20 are adapted to be engaged by a button 21 (see Fig. 7) having two heads and a connecting shank and being preferably of soft material to connect the front and rear flaps with each other under the crotch with a view to provide leg portions at the lower end of the body 10.

55 For long waisted persons the button 21 engages the lowermost buttonholes 19, 20 in the rear flaps 17, 18, and the lowermost buttonholes 15, 16 in the front flaps 11 and 12. For short-waisted persons the button 21 is engaged with the lowermost buttonholes 19, 20 in the rear flaps 17, 18 and with a pair 60 of upper buttonholes 15, 16 in the front flaps 11, 12. For very short-waisted persons the button 21 is engaged with a pair of upper buttonholes 19, 20 and a pair of upper buttonholes 15, 16 in the front flaps 11 and 12. 65

70 The lower front portions of the body 10 are provided with buttons 22 and 23, and the lower ends of the back flaps 17 and 18 are provided with buttonholes 24, 25, of which the buttonhole 24 is adapted to be engaged with either button 22 or 23, and the buttonhole 25 is adapted to be engaged with either button 22 or 23, as will be readily understood by reference to Figs. 1, 3, 4, 5 and 7. By the arrangement described, 75 the leg portions are snugly closed around the legs of the wearer, it being understood that when the button 21 is used higher up use is made of the buttonholes 24 or 25 and the buttons 22 (see Figs. 1, 3 and 4), 80 and when the button 21 is used in lowermost position use is made of the buttonholes 24 and 25 and the buttons 23 (see Figs. 5 and 7). It will also be noticed that by providing a number of buttonholes 15, 16 and 19, 85 20, the main button 21 can be engaged with the overlying flaps 11, 12 and 17, 18, to

- snugly close the garment in the crotch according to the form of the wearer's body. If the main button 21 is not used high up, it is desirable to close the front flaps 11 and 12 above the buttonhole, and for this purpose an auxiliary button 26 is used and engaged with a pair of registering buttonholes 15 and 16 next above the main button 21, as plainly indicated in Fig. 7.
- 10 From the foregoing it will be seen that by the arrangement described, the garment can be very quickly converted from an ordinary loose garment into one having leg portions or vice versa and while the garment is in position on the wearer's body.
- 15 Having thus described my invention, I claim as new and desire to secure by Letters Patent:
1. A combination garment, comprising a body split in a vertical direction along the median line of the front and back to form overlying front and back flaps, fastening means connecting all the front and back flaps with each other at the crotch, and fastening means for connecting the lower portion of each back flap to the lower portion of a corresponding front flap to provide leg portions at the lower end of the garment body.
- 20 2. A combination garment, comprising a body split in a vertical direction along the median line of the front and back to form overlying front and back flaps, the flaps being provided with buttonholes, a button engaging registering buttonholes of both front and back flaps for connecting the front and back flaps with each other at the crotch, and buttons on the front lower portions of the body and adapted to be engaged by buttonholes of the said back flaps.
- 25 3. A combination garment, comprising a body split in a vertical direction along the median line of the front and split in a vertical direction along the median line of the lower portion of the back to form overlying front and back flaps, the upper portions of the front flaps being provided with fastening devices for closing the upper front portion of the body, the lower portions of the
- 30 45 50 said front flaps being provided with buttonholes, the said back flaps being provided with

buttonholes, a main button engaging registering buttonholes of the said front and back flaps with each other, and buttons on the lower portions of the body and adapted to be engaged by buttonholes of the said back flaps.

4. A combination garment, comprising a body split in a vertical direction along the median line of the front, and split in a vertical direction along the median line of the lower portion of the back to form overlying front and back flaps, the upper portions of the front flaps being provided with fastening devices for closing the upper front portion of the body, the lower portions of the said front flaps being provided with buttonholes, the said back flaps being provided with buttonholes, a main button engaging registering buttonholes of the said front and back flaps with each other; buttons on the lower portions of the body and adapted to be engaged by buttonholes of the said back flaps, and supplementary buttons for fastening the overlapping front flaps together above the said main button.

5. A combination garment, comprising a body split in a vertical direction along the median line of the front and split in a vertical direction along the median line of the lower portion of the back to form overlying front and back flaps, the upper portions of the front flaps being provided with fastening devices for closing the upper front portion of the body, the lower portions of the said front flaps being provided with buttonholes, the said back flaps being provided with buttonholes, a main button engaging registering buttonholes of the said front and back flaps with each other, and two buttons on the front of each lower portion of the body and adapted to be engaged by the lowermost buttonhole of the corresponding back flap.

In testimony whereof I have signed my name to this specification in the presence of two subscribing witnesses.

FREDERICK E. SZEMERE.
